SAMPLING MACHINE

Clair V. Swearingen, Chattanooga, Tenn.

Original application July 7, 1941, Serial No. 401,396. Divided and this application March 26, 1942, Serial No. 436,337

3 Claims. (Cl. 73—21)

The subject matter of this application is a sampling machine, divided out of my former application, Serial No. 401,396, filed on July 7, 1941.

This invention is adapted to be used for collecting samples of liquid, for instance water, throughout any desired period of time, such as twenty-four hours. The operator may desire samples of liquid for fractions of that period, conveniently but not necessarily six-hour samples.

The liquid discharged during the fractions of the unit of time-measurement is delivered into containers. The invention aims to provide novel means for presenting the containers, one after another, to a source of liquid supply.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Fig. 1 is a vertical section through a sampling device embodying my invention;

Fig. 2 is a horizontal section thereof;

Fig. 3 is a section taken lengthwise of one of the troughs;

Fig. 4 is a transverse section through one of the troughs;

Fig. 5 is a sectional elevation showing the motor connection.

In carrying out the invention, there is provided a box-like support 1, having a movable closure 2. The support 1 and the closure 2 are insulated, as shown at 3, to the end that the samples may be kept an even temperature.

A removable frame 4 is located in the support or cabinet 1, and rests on the bottom thereof. The frame 4 is made up of corner legs 5, a top 6, a shelf 7, and an intermediate partition 8. Certain of the legs 5 are connected by a cross bar 9. The samples of liquid are collected in containers 10. When the containers 10 are not in use, they may be stowed on the shelf 7, in the compartment formed by the shelf and the partition 8.

A vertical shaft 12 is mounted at 15 for rotation in the top of the support or cabinet 1. A horizontal gear wheel 23 is secured to the upper end of the shaft 12. The gear wheel 23 meshes with a pinion 24 on the depending shaft 25 of a motor 26, mounted on the top 6 of the frame 4. Specifically, the motor 26 is of the spring-actuated clock type, so constructed that, for example, the shaft 12 will receive one rotation in twenty-four hours.

The aforesaid containers 10 are carried by a turntable 27, secured at 28 to the lower part of the shaft 12. The lower end of the shaft 12 is free, and, as stated in the parent application

15 No. 401,396, it should be noted that the shaft 12 and associated parts are suspended from the bearing means 15, which is carried by the top 6 of the frame 4. There is no lower thrust bearing for the shaft 12, a thrust bearing being an undesirable mechanism, which is difficult to keep in order, a thrust bearing, moreover, causing the shaft 12 to have a limited freedom of rotation. A circular rest 29 is secured to the shaft 12, above the turntable 27, and has circumferentially spaced notches or seats 30 in its periphery. Curved troughs or receivers 31 are supplied, and are equipped with handles 32, whereby they may be manipulated readily. The troughs 31 are mounted removably on the rest 29, to the end that they may be detached and kept in a sterile condition. The troughs 31 receive liquid, drop by drop, from a depending nozzle 33. The means for governing the flow of liquid through the nozzle 33 forms no part of the present invention and is disclosed in application Serial No. 401,396, to which reference has been made hereinbefore.

The troughs 31 are semi-circular. Each trough 31, at one end, is supplied with an upwardly inclined wall 34. At its opposite end, each trough 31 has an end wall 35, which is in the form of an inverted, V-shaped hook, receiving the end wall 34 of the next adjoining trough. Thus, the troughs 31 are interengaged detachably, and are held in the form of a circle.

45 Intermediate its ends, each trough 31 is supplied with an inverted, V-shaped divider 36. Assuming that it is desired to collect four samples, the trough structure 31 is divided into four receivers, each adapted, in its turn, to receive drip 50 from the nozzle 33, as the shaft 12 and associated parts are rotated. Owing to the inverted V-shape of the dividers 36, and to the inverted V-shape of the parts 34 and 35, the drip from the nozzle 33 into one trough will be terminated abruptly, 55 as to that trough, and will be received imme-

diately in the next adjoining trough, as the shaft 12 and the rest 29 are rotated.

Each compartment of each trough 31 has a depending spout 37, received in the corresponding notch 30 of the rest 29, to hold the annulus formed by the troughs, for rotation with the rotor. The notches 30 are inclined laterally with respect to the radii of the rest 29 which pass through them, thereby to hold the spouts the more firmly seated in the notches when the rotor is rotated in one direction. The containers 10 are so arranged on the turntable 27 that each spout 37 will discharge into one container. The inverted V-shape of the cross members 36 and 35—34 produces, as has been stated hereinbefore, a prompt shift of the discharge from the nozzle 33 into the respective compartments of the troughs 31, and the containers 10 receive samples of like volume, assuming that there is no general failure of liquid supply to the nozzle 33, due to the bursting of a water main, the closing of a gate valve, or the like.

The operation of the mechanism hereinbefore described is as follows:

The clock motor 28, the motor shaft 25, the pinion 24, and the gear wheel 23, rotates the shaft 12, the turntable 27, and the rest 29, at a predetermined speed, say one revolution in twenty-four hours, the parts 12—27—29 constituting a rotor. The drip from the nozzle 33 is received in the troughs 31, and passes by way of the spouts 37 into the containers 10.

The device is simple in construction, but will be found to be satisfactory and accurate in collecting samples of a liquid.

It may be noted that the nozzle 33 is connected to a supply pipe 39 mounted in the wall of the cabinet 1, a coupling 40 being employed, to connect the parts specified. The coupling 40 may be manipulated to disconnect the pipe 39 from the nozzle 33, and the frame 4 may be removed readily from the box-like support or cabinet 1.

What is claimed is:

1. A sampling device comprising a rotor mounted to turn about a substantially vertical axis, sample holders carried by the rotor and disposed about said axis, a supply source discharging material to be sampled, toward the holders, a rest incorporated in the rotor and provided with openings, troughs removably carried by the rest and provided with terminal, detachably-interengaged parts which hold the troughs in the form of an annulus, about said axis, said parts forming end closures for the troughs, the troughs being interposed between the supply source and the holders, each trough having a depending spout which is extended through one of the openings, to hold the annulus for rotation with the rotor, each spout discharging into one holder, and means for rotating the rotor.

2. A sampling device comprising a frame, a substantially vertical shaft, means for supporting the upper portion of the shaft for rotation in the upper portion of the frame, the lower end of the shaft being free, a turntable carried by the lower portion of the shaft, sample holders removably mounted on the turntable and disposed about the shaft, a rest carried by the shaft and disposed above the turntable, an annular trough structure removably mounted on the rest and provided with compartments having outlets individual to the holders, a source of supply for material to be sampled, discharging downwardly into the trough structure, and mechanism mounted on the upper portion of the frame for rotating the shaft.

3. A sampling device constructed as set forth in claim 1, and wherein the openings are notches in the periphery of the rest, the notches being inclined laterally with respect to radii of the rest which pass through them, thereby to hold the spouts the more firmly seated in the notches when the rotor is rotated in one direction.

CLAIR V. SWEARINGEN.
